UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed October 29, 1920. Serial No. 420,418.

To all whom it may concern:

Be it known that I, WALTER P. ALBERT, a citizen of the United States, residing at East Orange, in the county of Essex, State 5 of New Jersey, have invented certain new and useful Improvements in Telephone Systems, of which the following is a full, clear, concise, and exact description.

This invention relates to telephone systems and particularly to systems of the class 10 employing automatic switches for setting up talking connections.

Exchanges comprising many offices, each 15 of which is required to handle a large volume of local and interoffice traffic, when equipped to operate on the semiautomatic or full automatic basis are best served when the large capacity switches, particularly those of the power driven revertive impulse 20 type, are used for extending connections. These switches are capable of making rapid selections from large trunk or line groups permitting, thereby, efficiency in the operation of equipment installed and a marked 25 saving in time. To control the several selective movements of the switches in accordance with the revertive impulse principle, controlling mechanisms, such as the well-known register senders, are provided at the 30 central office. The function of the register sender is to receive the record of the desired call, and to thereupon control the selective switches in correspondence with the registered designation to extend a connection to 35 the wanted line or office. In semi-automatic systems where the calls are first received by, or are communicated to, an operator the record is set up on the registers by means of a keyboard manipulated by the operator. 40 In offices that are provided, however, with switches alone for performing the necessary extension of the calling lines the record for determining the selective operations must be produced on the central office sender by 45 means of impulses transmitted over the line from the calling substation or, perhaps, from distant operators' positions.

The complete designation or number relating to a particular call may be considered 50 as consisting of two parts. The first includes one or more digits and serves to identify the particular office in the exchange

that contains the called line. The second part is the number of the called line in the office. The first part, or the office code as 55 it may be called, is recorded on the sender in the office of the calling line and determines the selective movement of switches in that office to select a trunk leading to the outlying office identified by the recorded 60 code. Thereafter, the sender controls switches or other devices in the distant office in correspondence with the numerical or second part of the designation to cause 65 the further extension of the connection. In some cases the number of outlying offices 70 that a given office is called upon to serve is large. The sender in such office accordingly, must be capable of recording a large number of office designations. In order that the 75 requisite number of office codes may be registered to determine the routing of connections to outlying offices, and to care for the various classes of calls involved, and to secure a flexible arrangement whereby 80 these routings may be altered from time to time without the necessity of expensive and complex wiring changes, a switch, similar in many respects to the usual selector, is provided to record the office registrations. 85

The object of the invention is, therefore, to provide, in a system of the above described character, a switch having a plurality of movements, each movement caused by impulses sent over a calling line, to 90 register a desired designation to control the selective movement of switches for extending a talking connection.

A feature of the invention relates to the provision of a switch arranged to be driven, 95 step-by-step in a plurality of movements by series of impulses sent over the calling line, to a set position for controlling the selective operation of automatic switches for extending telephone connections.

Other and further features contemplated by the present invention will become obvious from a consideration of the following description.

Referring to the drawing Figs. 1, 2 and 3 100 when taken in order from left to right with Fig. 4 beneath Fig. 2 and Fig. 5 at the right of Fig. 4 illustrate a portion of the circuits and apparatus of a telephone office

in which the present invention is contained.

In Fig. 1 is shown a calling subscriber's line terminating in an individual line switch adapted to extend the line to an idle trunk circuit.

Fig. 2 illustrates a trunk circuit accessible to the individual line switch and which terminates in a first or district selector switch. This figure also shows a step-by-step 10 sender selector switch for associating the circuits of the district switch with one of a plurality of register sender mechanisms.

Fig. 3 shows a second, or office selector switch accessible to the district switch and which serves to extend the calling line over trunks to other switches either in the same or in distant offices.

Fig. 4 illustrates a sender and controlling mechanism arranged to receive series of impulses transmitted over a calling subscriber's line to record the office and numerical designation of a called subscriber's line and to control the automatic switches for the purpose of extending a connection in accordance with the registered designation. This figure also illustrates a class switch, the function of which is to govern the sending mechanism in accordance with the class of the 30 call recorded.

Fig. 5 shows diagrammatically a two movement step-by-step switch arranged to be positioned directly by impulses from the calling subscriber's line to determine the 35 routing of the connection to the proper office. This figure also shows a plurality of switches on which the numerical designation of the desired line in the called office may be registered.

The individual line switch shown in Fig. 1 and the district and office switches shown in Figs. 2 and 3 respectively are in general of the same kind as those shown in Patent No. 1,395,977, issued November 1, 1921, to 45 F. A. Stern and F. J. Scudder. The district and office switches are of the well-known power driven panel type, a complete description of their construction being given in the patent to Craft and Reynolds, 1,123,696, issued January 5, 1915.

The sequence switches 210, 310, 410 and 440 are the same in structure and principle as the one illustrated in detail in the patent to Reynolds and Baldwin, 1,127,808, patented February 9, 1915. The sequence switches 210 and 310 control respectively the contacts shown in Figs. 2 and 3. In Fig. 4, however, the sender sequence switch 440 governs all contacts shown in the space 60 above and to the right of the broken line, while the class sequence switch 410 controls the remaining contacts.

In the lower part of Fig. 4 a small step-by-step switch is shown having five brushes 65 411, 412, 413, 414 and 415, each cooperating

with a circular row of terminals. This switch performs the necessary change-over functions for associating the impulse circuit in succession with the switch and registers shown in Fig. 5. The brushes 411, 412, 413, etc. of the control switch are advanced from position to position by means of the stepping magnet 416, which is designed to step said brushes forward upon deenergization.

In the upper part of Fig. 5 are shown in a diagrammatic manner the brushes and terminal bank of a two motion step-by-step selector switch, which will be called herein after a translator switch. The translator comprises an ordinary step-by-step switch 75 having a primary vertical movement and a secondary rotary movement with certain modifications in the arrangement of the terminal bank to suit the purposes for which it is employed. As illustrated, the terminal bank is divided into six different sections, 505, 506, 507, 508, 509, and 510. Each of these sections has ten levels of ten terminals, comprising in all one hundred terminals. Cooperating with each section of one 90 hundred terminals is a brush, such as 511, 512, 513, etc. These brushes are all mounted on the same shaft and operated vertically by a magnet 504 and in the rotary movement by stepping magnet 503. In addition 95 to the six sections of one hundred terminals, the switch is provided with a vertical row of ten terminals 517. Brush 518 contacts with these terminals during the primary movement of the switch and is arranged to disengage the corresponding terminal when the switch is stepped in its rotary movement over a given level. The several contacts of the bank 505 are connected

to contacts, such as 472 and 473 of the class 105 sequence switch 410. By thus connecting the terminals of this bank to contacts of the class sequence switch, said sequence switch may be caused to take up positions in accordance with the level and terminal in the 110 level selected by the translator switch under the control of impulses sent from the calling subscriber's substation. The first two series of impulses cause the setting of the translator switch, identifying the particular 115 office to which the connection is going to be extended. According to the manner in which connections are handled in the called office, as, for example, in a full mechanical or semi-mechanical manner, the class sequence switch 410 takes up a setting to govern the operation of the sender in controlling the extension of the particular connection involved. Some of the outlying offices served through the office shown in the drawing will be provided with switches for handling incoming calls on a full mechanical basis. Calls to these offices constitute one 120 class. Again other offices will be equipped with call indicators at an operator's position 125

130

for completing the connections manually. These offices will constitute another class. Similarly there may be several other classes of calls that will have to be taken care of.

5 For this purpose the class sequence switch 410 is provided and is variably set, as will hereinafter be explained in detail, in accordance with the terminal on which the brush 511 is positioned. One position of the class sequence switch will be assigned for full mechanical calls, another position for call indicator calls, etc. In order that the class sequence switch may take up the proper setting, it only becomes necessary to connect 10 the terminals of the bank 505 to contacts 472, 473, etc. in their different closing positions in such a manner that, when the brush 511 is positioned on a particular terminal under the control of impulses sent from a 15 calling subscriber representing the code of an office relating to a given class of calls, the class sequence switch is driven to the corresponding position.

The terminals of the bank 506 of the 20 translator switch are connected arbitrarily to the different counting relays of the sender shown in Fig. 4, such that when brush 512 is set on a given one of the one hundred terminals a circuit is extended to the proper 25 point in the series of counting relays to control the selection of the necessary set of brushes of the district switch. Similarly the section 507 of the terminal bank has its 30 terminals wired to the counting relays for controlling district group selection, and the terminals of banks 508 and 509 are likewise wired to the counting relays for controlling office brush and office group selections respectively. From this explanation 35 it will be observed that a hundred different combinations may be secured by wiring the hundred terminals of the four sections 506, 507, 508 and 509, to different ones of the ten counting relays. The first two series of 40 impulses sent by the subscriber to position the translator switch determine the district brush, district group, office brush and office group selections to select a trunk, such as trunk 328, 329 leading to the office containing the called line. In other words the first 45 two letters or numerals identifying the called office determine the vertical and rotary movements of the translator switch for the purpose of selecting this office. In order, therefore, to make changes in the codes and 50 routings whenever the same becomes necessary, all that need be done is to change the manner in which the terminals of the translator bank are wired to the counting relays. 55 The translator switch is illustrated as having six sections in the terminal bank. While the last section 510 is not utilized in the present system, it may serve for any desired purpose where more than five brushes are 60 required.

In the lower part of Fig. 5 the numerical registers 540, 545, 550 and 555 are diagrammatically illustrated. These registers each consist of a rotary step-by-step switch having a plurality of brushes and cooperating terminal banks and each is propelled in a step-by-step movement by the respective stepping magnets 541, 546, 551 and 556. Following the transmission of the first two series of impulses for setting the translator switch, the subscriber sends four series of impulses identifying the digits of the called line number which cause the variable setting of the numerical registers. The banks of each of these registers may be wired in any convenient manner to the counting relays in order to control incoming and final switches or call indicators either in the local office or in a distant office selected by the district and office switches illustrated in Figs. 2 and 3. Inasmuch as the present invention relates more particularly to the translator switch and the manner of controlling the same over the calling line, it is not found necessary to illustrate and describe the controlling mechanism in further detail nor to show the different types of apparatus that may be installed in distant called offices. For a more extensive explanation of a register sender of this type reference is made to the above mentioned Patent No. 1,395,977, issued to Stearn and Scudder.

Having given a general explanation of the system it is believed a better understanding may now be had of the nature of the invention by describing in detail the operations concerned in the extension of a connection. For this purpose it will be assumed that the subscriber of line 100 desires to converse with a subscriber whose line terminates in an office identified by the code No. 37. In practice it is probably more convenient to identify the offices by letter codes which may be taken as abbreviations of the names of the offices. For example, the called office may be known by the code A B and the manipulation of the subscriber's dial 101 to transmit the letters A B would in effect cause the transmission of the digits 3 7.

To initiate a call the subscriber removes his receiver from the switchhook whereby a circuit is established from battery through the right-hand winding of line relay 103, back contact and inner lower armature or relay 104, over the loop of the calling substation 100, to ground at the upper armature and back contact of relay 104. Relay 103 becomes energized and completes a circuit from battery through the winding of stepping magnet 105, armature and contact of said magnet, lowermost armature and contact of relay 104, right-hand armature and front contact of relay 103 to ground through the brush 111 and terminal 114. Magnet 105 energizes, interrupts its own circuit, de-

energizes, and steps the brushes 106, 107, 108, 109, 110 and 111 forward one step. Brush 109 thereupon engages the segment 113 and battery potential is supplied to the test terminal 102 of the calling line 100 in the multiple banks of all final selector switches having access to this line. In this manner the calling line is rendered busy. The above traced circuit is again completed for magnet 105 by way of brush 111 and terminal 119, and the switch continues to the next set of terminals which represent the first of a plurality of trunk circuits leading to district selector switches. So long as the individual switch encounters the terminals of busy trunks, brush 111 finds a ground potential on the test terminals 120 of such trunks and the switch continues to rotate. When the first idle trunk 115, 116 is reached no ground potential is present on terminal 120 and, consequently, the stepping magnet 105 ceases to advance the switch.

Since the trunk 115, 116 is idle, the sequence switch 210 of the district switch associated with such trunk is standing in position 1. A circuit is then closed from battery through contact 203 (1), back contact and left-hand armature of relay 206, conductor 118, terminal 120, brush 111, contact and left-hand armature and left-hand winding of relay 103, through both windings of relay 104, in series, to ground. Relay 104 becomes energized in this circuit and locks up in a circuit as follows: battery, through the winding of relay 206, left-hand make-before-break contact of relay 205, lower contact 245 (1+2½), conductor 117, terminal 121, brush 110, middle lower armature and contact of relay 104, upper winding of said relay to ground. Relay 104, therefore, remains energized, while relay 206 also attracts its armatures. Relay 206, at its left-hand armature and back contact, opens the circuit through the left-hand winding of relay 103, which caused the original energization of relay 104. Relay 103, consequently, becomes deenergized.

Relay 206, on attracting its armatures, completes a circuit from battery through the right-hand winding of relay 212, lower left-hand contact 214 (1), right-hand contact 208 (1+10), left-hand contact 208 (1+3), to ground at the contact and right-hand armature of relay 206. Relay 212 becomes energized and closes a circuit from battery through the winding of sequence switch magnet 210, left-hand contact 215 (1), front contact and right-hand armature of relay 212, lower contact 213 (1+6), to ground. Sequence switch 210 advances from position 1 to position 2. A circuit is now closed from ground over upper left-hand contact 209 (2+18-1¼) conductor 118 to multiples of terminal 120 to hold the trunk busy. Should the test brush 241 of the send-

er selector switch chance to be standing on the terminals of a busy sender at this time, relay 207 of some other switch is energized, as will be later explained, and a circuit is provided for maintaining the operation of relay 212. This circuit may be traced from battery through the left-hand winding and contact and left-hand armature of relay 212, upper left-hand contact 251 (1+6), lower contact 220 (1+2-1¼), conductor 252, brush 241, thence over the multiple of the test terminal individual to the busy sender, to the brush 241 of the sender selector that is rendering said sender busy, to ground at the inner left-hand armature of the operated relay corresponding to the relay 207, shown in the figure. Relay 212 remains energized in position 2 of sequence switch 210, and, in so doing, provides a circuit for the stepping magnet 211 for advancing the brushes 239, 240, 241, 242, 243, and 244 of the sender selector switch shown, to search for the terminals of an idle sender. The circuit for magnet 211 may be followed from battery through the contact and armature and winding of said magnet, conductor 253, left-hand contact 218 (1-3¼+2), front contact and right-hand armature of relay 212, lower contact 213 (1+6), to ground. At the same time a circuit is maintained from battery through the contact and armature and winding of magnet 211, through the winding of relay 207, to ground at the lower left-hand contact 209 (2+11). Due, however, to the shunt provided by the above traced circuit, sufficient current does not flow through the winding of relay 207 to energize the latter. Stepping magnet 211 interrupts its own circuit and advances the brushes of the sender selector in a step-by-step movement to search for an idle register sender. When the first idle sender is reached, relay 212 becomes deenergized since no ground potential is found on the multiple terminal engaged by the test brush 241. Relay 212 opens the direct circuit to ground for the magnet 211. Magnet 211 is now included in series with relay 207, and this relay attracts its armatures. The magnet 211 does not continue to operate in view of the high resistance of relay 207. Relay 207, at its inner left-hand armature, applies a ground potential to the test terminal to render the selected sender busy to other sender selector switches. Relay 212, on retracting its armatures, completes a circuit as follows for driving the sequence switch 210 out of position 2 and into position 3: battery, through the winding of said sequence switch, right-hand contact 215 (2), back contact and right-hand armature of relay 212, lower contact 213 (1+6), to ground. Relay 207 also closes a circuit from ground over its inner left-hand armature, brush 241, contacts 403 of the class sequence switch 410, winding of

relay 402 to battery and ground. Relay 402 locks up over its inner armature and at its outer armature closes a circuit by way of upper left-hand contact 408 for driving sequence switch 410 into position 3.

An idle sender having been selected, and with sequence switch 210 in position 3, an impulse circuit is established from the calling subscriber's line through to the impulse relay 400 of said sender. This circuit may be traced from battery through the winding of impulse relay 400, brush 240, outer left-hand armature and contact of relay 207, lower contact 201 ($2+10-\frac{1}{2},$) conductor 116, terminal 122, brush 108, front contact and inner lower armature of relay 104, through the loop of substation 100, upper armature and front contact of relay 104, brush 106, terminal 123, conductor 115, left-hand contact 200 ($2+10\frac{1}{2},$) brush 239, right-hand winding of coil 401, to ground. Relay 400 becomes energized and completes a circuit over its armature and front contact for the slow to release relay 404. Relay 404 closes a circuit from ground through its outer left-hand armature and contact, conductor 425, vertical off normal contact 531, winding of relay 500 to battery and ground. Contact 531 is controlled by the shaft of the translator switch and is closed during the time said shaft is in its normal position. Relay 404 also completes a circuit from ground through the right-hand winding of the tone coil 475, left-hand winding of coil 401, inner left-hand armature and contact of relay 404, conductor 409, terminal 434, brush 414 of the control switch, to ground. Current flowing in this circuit induces a current in the right-hand winding of the coil 401, which is transmitted over the impulse circuit above traced, to produce a characteristic sound in the calling subscriber's receiver. This sound indicates that a sender has been associated with the calling line and that the subscriber may proceed to transmit impulses.

The subscriber thereupon operates the sending dial 101 to transmit the first digit 3 of the code identifying the office in which the called line appears. The first interruption of the impulse circuit causes the de-energization of relay 400, which completes a circuit from ground through its armature and back contact, right-hand armature and front contact of relay 404, winding of the slow to release relay 405, brush 412, terminal 417, conductor 424, inner right-hand armature and front contact of relay 500, conductor 559, winding of the vertical stepping magnet 504 to battery and ground. The retraction of the armature of relay 400 also completes a circuit from battery through the winding of relay 406, brush 413, terminal 433, conductor 422, contact and outer left-hand armature of relay 500, conductor

560, contact and armature of magnet 504, conductor 559, front contact and inner right-hand armature of relay 500, conductor 424, terminal 417, brush 412, winding of relay 405, front contact and right-hand armature of relay 404 to ground at the back contact and armature of relay 400. Relay 403 becomes energized and completes a circuit from ground through its outer armature and contact, winding of relay 405, brush 412, terminal 417, conductor 424, and thence, as above traced, through the winding of magnet 504 to battery and ground. Relay 403 is, therefore, energized in a circuit which depends upon the armature and contact of the vertical stepping magnet 504, and as long as it remains energized a circuit for said magnet is maintained independently of the armature and back contact of relay 400. Should the opening period of the line circuit be abnormally short due to an imperfect dial, or for any other reason, the consequent attraction of the armature of relay 400 does not cause the premature opening of the circuit of the stepping magnet 504. The magnet 504 remains energized, depending upon the relay 406, until it has had time to advance the brushes of the switch a full step to position them opposite the first levels of terminals. When the full step has been completed the armature and contact of relay 504 are opened and the circuit of relay 406 is interrupted. Relay 406 thereupon releases its armatures and opens the circuit of the magnet 504, which in turn becomes deenergized. Relay 406, furthermore, maintains a circuit at its inner armature and contact for the slow to release relay 404. Relay 404 is designed to remain operated during the normal periods in which its circuit is opened by the armature of relay 400. If, however, relay 400 remains deenergized for an exceedingly long period, relay 404 cannot become deenergized due to the fact that relay 406 provides a substitute holding circuit therefor.

As the translator switch takes its first step, the contact 531 is opened to interrupt the original energizing circuit of relay 500. Relay 500, however, remains energized in a circuit as follows: battery, through the winding and front contact and inner left-hand armature of relay 500, conductor 423, contact and armature of the slow to release relay 405, to ground. Relay 405, being of the slow-to-release character, does not retract its armature during the brief interruptions of its circuit at the armature and back contact of the stepping relay 400. On each of the following interruptions of the line circuit in the transmission of the first digit, the brushes 511, 512, 513, 514, 515 and 516 of the translator switch are advanced one step until they are finally positioned opposite the third levels of terminals in their

respective banks. Following the third impulse, the stepping relay 400 remains energized for a comparatively long period, during which interval the slow-to-release relay 405 is permitted to release its armature. Relay 405 opens the holding circuit of relay 500, which becomes deenergized.

The calling subscriber next operates the sending dial 101 to transmit a series of seven impulses representing the second digit of the office code. On the first opening of the impulse circuit, relay 400 becomes deenergized and completes a circuit from ground through its armature and back contact, right-hand armature and front contact of relay 404, winding of relay 405, brush 412, terminal 417, conductor 424, inner right-hand armature and back contact of relay 500, conductor 561, winding of the rotary stepping magnet 503 to battery and ground. A circuit is also closed for the energization of relay 406 as follows: battery, through the winding of said relay, brush 413, terminal 433, conductor 422, left-hand normal contact of relay 500, conductor 562, contact and armature of stepping magnet 503, conductor 561, and thence to ground, as above traced, at the back contact and armature of relay 400. Relay 406, in a manner similar to that described, closes a locking circuit for the rotary stepping magnet 503 to insure that said magnet takes a full step before its circuit is opened. For each of the seven impulses of the second digit the brushes of the translator switch are advanced one step over the third levels of terminals and are finally brought to rest in engagement with the seventh terminals 522, 523, 524, 525 and 526. The slow-to-release relay 405, which also becomes energized during the transmission of the second series of impulses, completes a circuit from ground through its armature and contact conductor 423, inner left-hand armature and back contact of relay 500, conductor 427, winding of the stepping magnet 416 to battery and ground. Magnet 416 energizes preparatory to advancing the brushes of the control switch when its circuit is opened. After the last impulse has been transmitted, relay 400 remains energized for a period of time sufficient to permit the release of the slow relay 405. Relay 405 opens the circuit of stepping magnet 416, which in turn deenergizes and advances the brushes 411, 412, 413, 414 and 415 to their second position terminals.

The two movement step-by-step selective switch has thus been positioned in accordance with the office code to determine the operation of the district and office switches to route the call in the proper direction. The calling subscriber continues to manipulate his dial to transmit the digits corresponding to the numerical designation of the

wanted line. In a ten thousand line office the subscriber's line numbers consist of four digits and consequently four numerical registers 540, 545, 550 and 555 are provided to take a record of these numbers. When the dial 101 is operated to transmit the first digit of the wanted number, relay 400 becomes deenergized and completes a circuit from ground through its armature and back contact, right-hand armature and front contact of relay 404, winding of relay 405, brush 412, terminal 418, conductor 429, winding of stepping magnet 541 to battery and ground. Magnet 541 energizes and upon its circuit being broken at the end of the first impulse advances the brushes 542, 543, etc. to the first position terminals. In a similar manner, for each succeeding impulse in the series, the brushes of register 540 are advanced step-by-step until a position corresponding to the first digit is reached. Relay 405 completes the circuit above traced for the stepping magnet 416, and at the end of the series this relay releases to permit the deenergization of said magnet. The brushes 411, 412, 413, etc. of the control switch are advanced to their third position terminals.

The energization of relay 400 in response to the transmission of the second series of impulses of the wanted line number causes a circuit to be closed from ground through the armature and front contact of relay 404, winding of relay 405, brush 412, terminal 419, conductor 430, winding of stepping magnet 546 of the next register, to battery and ground. The register 545 is thereupon moved forward step-by-step in response to the second series of impulses. Relay 405 closes the above traced circuit for the stepping magnet 416, and at the end of the series opens this circuit to permit the control switch to advance to the fourth position.

In a similar manner the next and last two series of impulses are directed to the stepping magnets 551 and 556 of the registers 550 and 555 respectively, and these registers take up their corresponding positions. Following the transmission of the last series of impulses the control switch is advanced to its sixth position.

The circuits of this system are arranged to start the district and office selections immediately following the setting of the translator switch, or, in other words, as soon as the record of the called office has been received. While the district and office switches are being positioned the subscriber may continue the dialing operation to register the number of the called line.

Immediately that the translator switch has been positioned, the control switch is moved to its second position terminals as explained. A circuit is then closed from battery through the winding of relay 407, terminal 485, brush 414 to ground. Relay 407 becomes energized

and locks up in a circuit from battery through the winding and outer armature and contact of said relay, upper contact 474 (1 $\frac{3}{4}$ +18) of the class sequence switch 410 to ground. It will be recalled the sequence switch 410 is standing in position 3. Relay 407 completes a circuit from ground through its inner armature and contact, left-hand armature and back contact of relay 471, lower right-hand contact 408 (3+15), winding of sequence switch magnet 410, to battery and ground. Sequence switch 410 is energized in this circuit and commences to rotate to take up the position corresponding to the class of the call that is being made by the calling subscriber. Said sequence switch will rotate as long as relay 471 remains de-energized and this relay will only become energized when the particular one of contacts 472, 473, etc., corresponding to the position which the translator switch has taken, is closed. In the present instance it is assumed that position 10 of sequence switch 410 represents the class of the call under consideration. When, therefore, sequence switch 410 reaches position 10, a circuit is completed from battery through the winding of relay 471, upper right-hand contact 472 (9+10), conductor 476, terminal 522, brush 511 to ground. Relay 471 becomes energized and locks up in a circuit from battery through its winding and right-hand armature and contact, lower contact 474 (4+17) to ground. Relay 471, at its left-hand armature and back contact, opens the above traced circuit of sequence switch 410 and this sequence switch comes to rest in position 10. Furthermore, relay 471 completes a circuit for advancing the sender sequence switch 440 out of position 1 and into position 2. This circuit may be traced from battery through the winding of the magnet of sequence switch 440, upper right-hand contact 439 (1), front contact and left-hand armature of relay 471, contact and inner armature of relay 407 to ground.

With the sender sequence switch in position 2, the fundamental circuit is closed as follows to control the selection of the proper set of brushes at the district switch: battery, through the left-hand winding of relay 212, upper right-hand contact 251 (3), lower left-hand contact 251 (3+6), contact and right-hand armature of relay 207, brush 242, contact 447 (4+13 $\frac{1}{2}$), contact 443 (2), winding of the stepping relay 445, armature and contact of relay 466, contact 444 (2) to ground. Relay 212 becomes energized and completes a circuit from battery through the winding of sequence switch magnet 210, left-hand contact 215 (3), front contact and right-hand armature of relay 212, lower contact 218 (1+6) to ground. Sequence switch 210 advances from position 3 into position 4. In position 4, relay 212 remains

energized in a circuit from battery through the left-hand winding, contact and left-hand armature of said relay, upper left-hand contact 251 (1+6), lower left-hand contact 251 (3+6), and thence to ground, as described, over the fundamental circuit. Relay 212 completes a circuit for the updrive power magnet 224 to cause the upward movement of the brush shaft 248. This circuit may be traced from battery through the winding of power magnet 224, right-hand contact 218 (4), front contact and right-hand armature of relay 212, to ground at the lower contact 213. 70 75

The stepping relay 445, which also energizes in series with relay 212, completes a circuit from ground through its armature and contact, upper contact 465 (2), conductor 469, brush 512 of the translator switch, terminal 523, conductor 527, and thence to conductor 455, Fig. 4, armature and back contact of relay 449, winding of relay 450 to battery and ground. Relay 450 becomes energized and completes a circuit for itself in series with relay 449 as follows: battery, 80 through the windings of relays 450 and 449, contact and armature of relay 450, lower contact 463 (2) to ground. Relay 449, however, does not become energized since its winding is shunted out by the direct circuit 85 to ground through the armature of the stepping relay 445. As the brush shaft 248 approaches the first brush tripping position a brush 288 encounters the first metallic segment of commutator 230 and a circuit is 90 closed as follows: battery, through the left-hand winding and contact and left-hand armature of relay 212, upper left-hand contact 251 (1+6), upper contact 220 (3 $\frac{3}{4}$ +4), commutator 230, brush 228, contact 223 95 (9+7) to ground. Relay 212 remains energized in this circuit and the stepping relay 445 in the fundamental circuit is shunted out. Relay 445 deenergizes and removes the shunt from around the winding 100 of the counting relay 449, permitting this latter relay to energize in series with relay 450. The brush shaft 248 continues to advance and brush 228, engaging the next insulating segment, permits the energization 105 of relay 445. The stepping circuit is now extended by way of conductor 455 to the armature and front contact of relay 449, armature and back contact of relay 451, winding of relay 452 to battery and ground. In a like manner for each brush tripping position approached by the brush shaft 248, a pair of counting relays are energized and locked up until finally the No. 0 counting 110 relay 454 becomes energized. Relay 454 closes a holding circuit for itself in series 115 parallel with the windings of relays 453 and 466. This circuit may be traced from battery through the winding of relay 454, whence it divides, one branch leading 120

through the winding of relay 453 and the other branch leading through the winding of relay 466, and thence to the contact and armature of relay 454, lower contact 463 (2) to ground. As the brush 228 encounters the next metallic segment following the energization of relay 454, the stepping relay 445 deenergizes and permits the operation of relays 453 and 466. Relay 466 opens the fundamental circuit, and relay 453 completes a circuit from ground through its armature and contact, contact 441 (2), winding of the magnet of the sequence switch 440 to battery and ground. Sequence switch 440 advances 10 out of position 2 and into position 4. As sequence switch 440 leaves position 2, the lower and upper contacts 463 are opened to permit the release of all counting relays that have been energized.

20 As soon, following the opening of the fundamental circuit at the sender, as brush 228 engages an insulating segment of commutator 230, relay 212 releases its armatures and opens the circuit of the updrive power magnet 224, causing the brush shaft 248 to come to rest. Relay 212 also completes a circuit from battery through the winding of sequence switch magnet 210, right-hand contact 215 (4), back contact and 25 right-hand armature of relay 212, to ground at the lower contact 213 (1+6). Sequence switch 210 thereupon advances into position 5. In this position a circuit is closed from battery through the winding of trip magnet 225, contact 221 (5+6) to ground. Magnet 225 becomes energized and rotates the trip spindle preparatory to tripping the selected set of brushes upon the next upward movement of the brush shaft 248.

40 With the sequence switch 210 in position 5 and the sender sequence switch 440 in position 4, the fundamental circuit is again closed to control group selection at the district switch. This circuit corresponds to 45 the one hereinbefore traced with the exception that the contacts of sequence switches 210 and 440 are closed in different positions. Relay 212, upon energizing in the fundamental circuit, closes a circuit for driving sequence switch 210 out of position 5 and into position 6. This circuit leads from battery through the winding of the magnet of said sequence switch, left-hand contact 215 (5), front contact and right-hand armature of relay 212, lower contact 213 (1+6) to ground. Relay 212 remains energized in position 6 of sequence switch 210 by means 50 of the locking circuit from battery through its left-hand winding and contact and left-hand armature, upper left-hand contact 215 (1+6), lower left-hand contact 215 (3+6) to contact at the fundamental circuit as described. Relay 212 again closes the circuit for the updrive power magnet 224 over the 60 right-hand contact 218, closed in position 6.

Brush shaft 248 is advanced and brushes 233, 234 and 235 are tripped into engagement with the terminals of the bank.

The stepping relay 445, which also energizes in the fundamental circuit, completes a circuit from ground through its armature and contact, lower contact 465 (4), conductor 470, brush 513, terminal 524, conductor 523, thence to conductor 457, Fig. 4, armature and back contact of the No. 9 70 counting relay 461, winding of the No. 9 counting relay 462 to battery and ground. Relay 462 becomes energized and prepares a series holding circuit for itself and relay 461. As the brush shaft 248 approaches the 80 first group of terminals, brush 227 engages the first metallic segment of commutator 231, and a circuit is closed from battery through the lefthand winding and contact and left-hand armature of relay 212, upper 85 left-hand contact 251 (1+6), lower right-hand contact 251 (5 $\frac{3}{4}$ +6), commutator 231, brush 227, contact 223 (9+7) to ground. Relay 212 remains energized and the stepping relay 445 is shunted out. Relay 445 90 deenergizes and permits the energization of relay 461 in series with relay 462. In a like manner, succeeding pairs of counting relays are energized and locked up and the brushes 233, 234 and 235 pass over succeeding groups of terminals. The 0 counting relays 454, 453 and 466 are finally energized and the fundamental circuit is opened. Relay 453 closes a circuit including contact 441 95 (4) for driving the sender sequence switch 440 out of position 4 and into position 6. As sequence switch 440 leaves position 4, the contacts 463 are opened and the energized counting relays release their armatures.

100 As soon, following the opening of the fundamental circuit at the armature and contact relay 466, as brush 227 encounters an insulating segment of the commutator 231, relay 212 becomes deenergized and opens the circuit of the updrive power magnet 224. Relay 212 also closes a circuit from battery through the winding of sequence switch magnet 210, right-hand contact 215 (6), back contact and right-hand armature 105 of relay 212, lower contact 213 (1+6) to ground. Sequence switch 210 thereby advances from position 6 into position 7. With the district sequence switch 210 in 110 position 7, a circuit is immediately closed from battery through the right-hand winding of relay 212, lower left-hand contact 214 (7+7 $\frac{1}{4}$), upper right-hand contact 208 (1+10), upper left-hand contact 208 (7+8), contact and right-hand armature of relay 206 to ground. Relay 212 becomes energized and completes a circuit from battery through the winding of sequence switch magnet 210, left-hand contact 215 (7), 115 front contact and right-hand armature of 120 relay 206 to ground. Relay 212 becomes energized and completes a circuit from battery through the winding of sequence switch magnet 210, left-hand contact 215 (7), front contact and right-hand armature of 125 relay 206 to ground. Relay 212 becomes energized and completes a circuit from battery through the winding of sequence switch magnet 210, left-hand contact 215 (7), front contact and right-hand armature of 130

and locks up in a circuit from battery through the winding and outer armature and contact of said relay, upper contact 474 (13/4+18) of the class sequence switch 410 to ground. It will be recalled the sequence switch 410 is standing in position 3. Relay 407 completes a circuit from ground through its inner armature and contact, left-hand armature and back contact of relay 471, lower right-hand contact 408 (3+15), winding of sequence switch magnet 410, to battery and ground. Sequence switch 410 is energized in this circuit and commences to rotate to take up the position corresponding to the class of the call that is being made by the calling subscriber. Said sequence switch will rotate as long as relay 471 remains de-energized and this relay will only become energized when the particular one of contacts 472, 473, etc., corresponding to the position which the translator switch has taken, is closed. In the present instance it is assumed that position 10 of sequence switch 410 represents the class of the call under consideration. When, therefore, sequence switch 410 reaches position 10, a circuit is completed from battery through the winding of relay 471, upper right-hand contact 472 (9+10), conductor 476, terminal 522, brush 511 to ground. Relay 471 becomes energized and locks up in a circuit from battery through its winding and right-hand armature and contact, lower contact 474 (4+17) to ground. Relay 471, at its left-hand armature and back contact, opens the above traced circuit of sequence switch 410 and this sequence switch comes to rest in position 10. Furthermore, relay 471 completes a circuit for advancing the sender sequence switch 440 out of position 1 and into position 2. This circuit may be traced from battery through the winding of the magnet of sequence switch 440, upper right-hand contact 439 (1), front contact and left-hand armature of relay 471, contact and inner armature of relay 407 to ground.

With the sender sequence switch in position 2, the fundamental circuit is closed as follows to control the selection of the proper set of brushes at the district switch: battery, through the left-hand winding of relay 212, upper right-hand contact 251 (3), lower left-hand contact 251 (3+6), contact and right-hand armature of relay 207, brush 242, contact 447 (4+13 1/2), contact 443 (2), winding of the stepping relay 445, armature and contact of relay 466, contact 444 (2) to ground. Relay 212 becomes energized and completes a circuit from battery through the winding of sequence switch magnet 210, left-hand contact 215 (3), front contact and right-hand armature of relay 212, lower contact 213 (1+6) to ground. Sequence switch 210 advances from position 3 into position 4. In position 4, relay 212 remains

energized in a circuit from battery through the left-hand winding, contact and left-hand armature of said relay, upper left-hand contact 251 (1+6), lower left-hand contact 251 (3+6), and thence to ground, as described, over the fundamental circuit. Relay 212 completes a circuit for the updrive power magnet 224 to cause the upward movement of the brush shaft 248. This circuit may be traced from battery through the winding of power magnet 224, right-hand contact 218 (4), front contact and right-hand armature of relay 212, to ground at the lower contact 213. 70 75

The stepping relay 445, which also energizes in series with relay 212, completes a circuit from ground through its armature and contact, upper contact 465 (2), conductor 469, brush 512 of the translator switch, terminal 523, conductor 527, and thence to conductor 455, Fig. 4, armature and back contact of relay 449, winding of relay 450 to battery and ground. Relay 450 becomes energized and completes a circuit for itself in series with relay 449 as follows: battery, through the windings of relays 450 and 449, contact and armature of relay 450, lower contact 463 (2) to ground. Relay 449, however, does not become energized since its winding is shunted out by the direct circuit to ground through the armature of the stepping relay 445. As the brush shaft 248 approaches the first brush tripping position a brush 288 encounters the first metallic segment of commutator 230 and a circuit is closed as follows: battery, through the left-hand winding and contact and left-hand armature of relay 212, upper left-hand contact 251 (1+6), upper contact 220 (3 3/4+4), commutator 230, brush 228, contact 223 (9+7) to ground. Relay 212 remains energized in this circuit and the stepping relay 445 in the fundamental circuit is shunted out. Relay 445 deenergizes and removes the shunt from around the winding of the counting relay 449, permitting this latter relay to energize in series with relay 450. The brush shaft 248 continues to advance and brush 228, engaging the next insulating segment, permits the energization of relay 445. The stepping circuit is now extended by way of conductor 455 to the armature and front contact of relay 449, armature and back contact of relay 451, winding of relay 452 to battery and ground. In a like manner for each brush tripping position approached by the brush shaft 248, a pair of counting relays are energized and locked up until finally the No. 0 counting relay 454 becomes energized. Relay 454 closes a holding circuit for itself in series parallel with the windings of relays 453 and 466. This circuit may be traced from battery through the winding of relay 454, whence it divides, one branch leading 80 85 90 95 100 105 110 115 120 125 130

- through the winding of relay 453 and the other branch leading through the winding of relay 466, and thence to the contact and armature of relay 454, lower contact 463 (2) to ground. As the brush 228 encounters the next metallic segment following the energization of relay 454, the stepping relay 445 deenergizes and permits the operation of relays 453 and 466. Relay 466 opens the fundamental circuit, and relay 453 completes a circuit from ground through its armature and contact, contact 441 (2), winding of the magnet of the sequence switch 440 to battery and ground. Sequence switch 440 advances out of position 2 and into position 4. As sequence switch 440 leaves position 2, the lower and upper contacts 463 are opened to permit the release of all counting relays that have been energized.
- As soon, following the opening of the fundamental circuit at the sender, as brush 228 engages an insulating segment of commutator 230, relay 212 releases its armatures and opens the circuit of the updrive power magnet 224, causing the brush shaft 248 to come to rest. Relay 212 also completes a circuit from battery through the winding of sequence switch magnet 210, right-hand contact 215 (4), back contact and right-hand armature of relay 212, to ground at the lower contact 213 (1+6). Sequence switch 210 thereupon advances into position 5. In this position a circuit is closed from battery through the winding of trip magnet 225, contact 221 (5+6) to ground. Magnet 225 becomes energized and rotates the trip spindle preparatory to tripping the selected set of brushes upon the next upward movement of the brush shaft 248.
- With the sequence switch 210 in position 5 and the sender sequence switch 440 in position 4, the fundamental circuit is again closed to control group selection at the district switch. This circuit corresponds to the one hereinbefore traced with the exception that the contacts of sequence switches 210 and 440 are closed in different positions. Relay 212, upon energizing in the fundamental circuit, closes a circuit for driving sequence switch 210 out of position 5 and into position 6. This circuit leads from battery through the winding of the magnet of said sequence switch, left-hand contact 215 (5), front contact and right-hand armature of relay 212, lower contact 213 (1+6) to ground. Relay 212 remains energized in position 6 of sequence switch 210 by means of the locking circuit from battery through its left-hand winding and contact and left-hand armature, upper left-hand contact 215 (1+6), lower left-hand contact 215 (3+6) to contact at the fundamental circuit as described. Relay 212 again closes the circuit for the updrive power magnet 224 over the right-hand contact 218, closed in position 6.
- Brush shaft 248 is advanced and brushes 233, 234 and 235 are tripped into engagement with the terminals of the bank.
- The stepping relay 445, which also energizes in the fundamental circuit, completes a circuit from ground through its armature and contact, lower contact 465 (4), conductor 470, brush 513, terminal 524, conductor 528, thence to conductor 457, Fig. 4, armature and back contact of the No. 9' counting relay 461, winding of the No. 9 counting relay 462 to battery and ground. Relay 462 becomes energized and prepares a series holding circuit for itself and relay 461. As the brush shaft 248 approaches the first group of terminals, brush 227 engages the first metallic segment of commutator 231, and a circuit is closed from battery through the lefthand winding and contact and left-hand armature of relay 212, upper left-hand contact 251 (1+6), lower right-hand contact 251 (5 $\frac{3}{4}$ +6), commutator 231, brush 227, contact 223 (9+7) to ground. Relay 212 remains energized and the stepping relay 445 is shunted out. Relay 445 deenergizes and permits the energization of relay 461 in series with relay 462. In a like manner, succeeding pairs of counting relays are energized and locked up and the brushes 233, 234 and 235 pass over succeeding groups of terminals. The 0 counting relays 454, 453 and 466 are finally energized and the fundamental circuit is opened. Relay 453 closes a circuit including contact 441 (4) for driving the sender sequence switch 440 out of position 4 and into position 6. As sequence switch 440 leaves position 4, the contacts 463 are opened and the energized counting relays release their armatures.
- As soon, following the opening of the fundamental circuit at the armature and contact relay 466, as brush 227 encounters an insulating segment of the commutator 231, relay 212 becomes deenergized and opens the circuit of the updrive power magnet 224. Relay 212 also closes a circuit from battery through the winding of sequence switch magnet 210, right-hand contact 215 (6), back contact and right-hand armature of relay 212, lower contact 213 (1+6) to ground. Sequence switch 210 thereby advances from position 6 into position 7. With the district sequence switch 210 in position 7, a circuit is immediately closed from battery through the right-hand winding of relay 212, upper left-hand contact 214 (7+7 $\frac{1}{4}$), upper right-hand contact 208 (1+10), upper left-hand contact 208 (7+8), contact and right-hand armature of relay 206 to ground. Relay 212 becomes energized and completes a circuit from battery through the winding of sequence switch magnet 210, left-hand contact 215 (7), front contact and right-hand armature of

relay 212, upper contact 213 (7+8), right-hand armature and contact of relay 205 to ground. It will be noted that relay 205 was energized in position 2 of sequence switch 210 in a circuit including upper right-hand contact 209 (2+11). The sequence switch 210 advances out of position 7 and into position 8. Relay 212 remains operated provided the trunk in the group upon the terminals of which the brushes 233, 234, and 235 are standing is busy. In this case the test brush 235 is standing on a grounded test terminal and the following circuit is closed for relay 212: battery, through the left-hand winding and contact and left-hand armature of relay 212, upper left-hand contact 222 (7½+9), upper right-hand contact 222 (7+16), brush 235, and thence to the grounded test terminal of the busy trunk. It will be noted that the upper left-hand contact 222 does not close until in position 7½. This closure, however, takes place prior to the opening of the original energizing circuit of relay 212, as the lower left-hand contact 214 opens when sequence switch 210 moves out of position 7½. Relay 212 remaining energized a circuit is completed for the updrive power magnet 224 from battery through the winding of said magnet, right hand contact 218 (8), front contact and right-hand armature of relay 212, lower contact 213 (7½+16) to ground. The brush shaft 248 is driven upwardly and brushes 233, 234 and 235 pass over the bank terminals to search for an idle trunk. When the first idle trunk is encountered, no ground potential being found on the test terminal 238 thereof, relay 212 becomes deenergized and opens the circuit of the updrive power magnet 224. Relay 212 also closes a circuit as follows for driving sequence switch 210 out of position 8 and into position 10: battery, through the winding of the magnet of said sequence switch, right-hand contact 215 (8), back contact and right-hand armature of relay 212, lower contact 213 (7½+16) to ground. With sequence switch 210 in position 10, and the sender sequence switch 440 in position 6, the fundamental circuit is extended through to the office switch, shown in Fig. 3, for controlling brush selection. This circuit may be traced from battery through the right-hand winding of relay 300, lower left-hand contact 306 (1), left-hand contact 305 (1+4), conductor 249, terminal 236, brush 233, upper right-hand contact 246 (10+15), lower right-hand contact 246 (10), conductor 254, contact and right-hand armature of relay 207, brush 242, contact 447 (4+13½), contact 443 (6), winding of stepping relay 445, armature and contact of relay 466, contact 446 (6), brush 243, conductor 255, upper right-hand contact 247 (10), lower right-hand contact 247 (10+15), brush 234, terminal 237, conductor 250, contact 304 (1+4) to ground. Relay 300 becomes energized and closes a circuit from ground through its left-hand armature and front contact, lower left-hand contact 303 (1), winding of sequence switch magnet 310 to battery and ground. Sequence switch 310 advances out of position 1 and into position 2. Relay 300 remains energized in a locking circuit from battery through its right-hand winding and front contact and inner right-hand armature, outer right-hand armature and front contact of said relay, lower right-hand contact 306 (1+4), left-hand contact 305 (1+4), and thence to ground as traced over the fundamental circuit. Relay 300 completes a circuit for the updrive power magnet 317 as follows: battery, through the winding of said magnet, lower right-hand and upper left-hand contacts 302 (2), front contact and left-hand armature of relay 300 to ground. The brush shaft 326 is thereby advanced under the control of the power magnet 317.

When the stepping relay 445 energizes in the fundamental circuit it completes a circuit from ground through its armature and contact, upper contact 464 (6), conductor 467, brush 514 of the translator switch, terminal 525, conductor 529, thence to conductor 458, Fig. 4, armature and back contact of relay 459, winding of relay 460 to battery and ground. Relay 460 becomes energized and prepares a locking circuit for itself and relay 459. For each metallic segment of the commutator 314 encountered by the brush 312 a circuit is closed from battery through the right-hand winding, front contact and inner right-hand armature of relay 300, outer right-hand armature and contact of said relay, lower right-hand contact 306 (1+4), upper right-hand contact 306 (13½+2), commutator 314, brush 312 to ground. Relay 300 remains energized in this circuit and the stepping relay 445 is shunted. Consequently the counting relays are energized and locked up in succession until finally the zero relays become operated. The fundamental circuit is then opened through the armature and contact of relay 466 and a circuit is completed from ground through the armature and contact of relay 453, contact 441 (6), winding of sequence switch 440 to battery and ground. Sequence switch 440 advances into position 8 and the actuated counting relays are de-energized.

As soon after the opening of the fundamental circuit at the sender, as brush 312 engages an insulating segment on commutator 314, relay 300 releases its armatures and opens the circuit of the updrive power magnet 317. Relay 300 also completes a circuit from ground through its left-hand armature and back contact, lower right-

hand contact 303 (2), winding of sequence switch magnet 310, to battery and ground, driving said sequence switch out of position 2 and into position 3. The brush tripping magnet 318 is now energized in a circuit closed over the lower contact 309 (3+7). Magnet 318 rotates the trip spindle in order to cause the selected set of brushes to be tripped on the next upward movement of the brush shaft.

The fundamental circuit is closed once more for controlling the group selecting movement of the office switch and may be traced over the path hereinbefore described with the exception that the contacts of sequence switches 310 and 440 are now closed in positions 3 and 8 respectively. Relay 300 becomes energized and completes a circuit from ground through its left-hand armature and front contact, lower left-hand contact 303 (3), winding of sequence switch magnet 310 to battery and ground. Sequence switch 310 becomes energized and moves into position 4. In this position relay 300 remains energized in a locking circuit from battery through its right-hand winding and front contact and inner right-hand armature, outer right-hand armature of said relay, lower right-hand contact 306 (1+4), and thence to ground as described. Relay 300 prepares the operating circuit of the updrive power magnet 317, which includes the lower right-hand and upper left-hand contacts 302 closed in position 4. The brush shaft 326 is driven upwardly in the group selecting movement of the switch.

Upon the energization of the stepping relay 445 in the fundamental circuit, a circuit is completed from ground through the armature and contact of said relay, lower contact 464 (8), conductor 468, brush 515, terminal 526, conductor 530, thence to conductor 456, Fig. 4, winding of the 0 counting relay 454 to battery and ground. Relay 454 becomes energized and prepares circuits for itself and relays 453 and 466. As soon as the brushes 320, 321 and 322 approach the first group of terminals, brush 311 engages a metallic segment of commutator 315 and a circuit is closed from battery through the right-hand winding and front contact and inner right-hand armature of relay 300, outer right-hand armature and contact of said relay, lower right-hand contact 306 (1+4), upper left-hand contact 306 (3 $\frac{3}{4}$ +4), commutator 315, brush 311 to ground. The closure of this circuit causes the shunt of the stepping relay 445, which permits the energization of counting relays 453 and 466. Relay 466 opens the fundamental circuit while relay 453 completes a circuit including contact 441 (8) for driving the sender sequence switch 440 out of position 8.

Shortly after the fundamental circuit is

opened at the sender, the brush 311 engages an insulating position of the commutator segment 315 and relay 300 becomes deenergized. Relay 300 opens the circuit of the updrive power magnet 317 and completes a circuit as follows for driving sequence switch 310 out of position 4 and into position 5: battery, through the winding of the magnet of said sequence switch, lower right-hand contact 303 (4), back contact and left-hand armature of relay 300 to ground. With sequence switch 310 in position 5 a circuit is immediately closed as follows: battery, through the left-hand winding of relay 300, upper left-hand contact 301 (5+7), upper right-hand contact 301 (5) to ground. Relay 300 becomes energized and closes a circuit from ground through its left-hand armature and front contact, lower left-hand contact 303 (5), winding of sequence switch 310 to battery and ground. Sequence switch 310 advances into position 6. Relay 300 remains energized in this position provided the first trunk in the selected group, upon the terminals of which the brushes 320, 321 and 322 are now standing is engaged. The holding circuit for relay 300 may be followed from battery through the right-hand winding and front contact and inner right-hand armature of said relay, outer right-hand armature and contact of relay 300, lower right-hand contact 308 (5+18), upper right-hand contact 308 (5+6 $\frac{1}{4}$), brush 322 to the grounded test terminal. Relay 300, by remaining energized, completes a circuit for the updrive power magnet 317 including the lower right-hand and the upper left-hand contacts 302 (6). When the first set of idle terminals is encountered, relay 300 becomes deenergized and opens the circuit of the power magnet 317, whereby the brushes 320, 321 and 322 are arrested in engagement with said terminals. Relay 300, on retracting its armatures, completes a circuit from battery through the winding of sequence switch magnet 310, lower right-hand contact 303 (6), back contact and left-hand armature of relay 300 to ground. Sequence switch 310 advances from position 6 into position 7. In this position relay 300 is again energized by means of a circuit from battery through the left-hand winding of said relay, upper left-hand contact 301 (5+7), upper right-hand contact 301 (7) to ground. Relay 300 closes a circuit from battery through the winding of sequence switch magnet 310, lower left-hand contact 303 (7), front contact and left-hand armature of relay 300 to ground, whereby said sequence switch advances from position 7 into position 8. Relay 300 remains energized in position 8 of sequence switch 310 by means of a circuit from battery through the right-hand winding and front contact and inner right-hand armature of said relay, 139

outer right-hand armature and contact of relay 369, lower contact 308 (5+18), lower left-hand contact 308 (7+18), conductor 327, terminal 238, brush 235, upper right-hand contact 222 (7+16), lower right-hand contact 222 (8½+16) to ground.

- After the office switch has been positioned to select trunk 328, 329, the sender sequence switch 440 advances to positions assigned 10 for controlling succeeding switches or other mechanism in accordance with the numerical portion of the designation, as is clearly explained in the above named patent to F. A. Stearn and F. J. Scudder 1,395,977. When 15 the complete connection has been established, the sender sequence switch 440 reaches some position, such as position 14, and a circuit is closed from ground through the contact 448, brush 244, upper left-hand contact 214 (10), right-hand winding of relay 212 to battery and ground. Relay 212 is energized and completes a circuit from battery through the winding of sequence switch magnet 210, left-hand contact 215 (10), front contact and right-hand armature of relay 212, lower contact 213 (7½+16) to ground. Sequence switch 210 advances from position 10 into position 15. As the sequence switch 210 leaves position 11 the upper right-hand contact 209 is opened and the circuit of relay 205 is interrupted. Relay 205, however, remains energized by reason of a substitute circuit closed from battery through its winding, contact and armature of relay 204, right-hand armature and front contact of relay 205 to ground. Relay 204, it will be noted, becomes energized in series with the calling subscriber's line over a circuit closed by contacts 200 and 201 as 30 the sequence switch 210 reaches position 10½. This circuit includes the battery and the left-hand windings of repeating coil 202. When the district sequence switch 210 leaves position 11, relay 207 becomes de- 35 energized and removes the busy condition from the multiple terminals of other sender selector switches to permit this sender to be taken for use in extending subsequent connections. At the time the sender sequence 40 switch 440 reaches position 14 a condition is created for causing the release of the translator switch and the numerical registers. To release the translator switch a circuit is closed from battery through the winding of release magnet 502, off normal contact 532, contact 438 (14) to ground. The contact 532 is closed as long as the brush shaft of the translator switch is away from its normal position. Magnet 502 becomes energized and causes in the well-known manner the release of the switch. Another circuit is closed for restoring the control switch to its normal position. This circuit may be traced from battery through the winding of 45 the stepping magnet 416, armature and con-

tact of said magnet, conductor 477, brush 411, contact 438 (14) to ground. Magnet 416 interrupts its own circuit and advances the brushes of the control switch until they reach their tenth position terminals, at 70 which time brush 411 opens the stepping circuit of said magnet. In position 10 of the control switch a circuit is established from ground through the brush 414, terminal 478, conductor 479, thence through the 75 brushes 542, 547, 552 and 557 and the contacts and armatures and windings of the respective stepping magnets 541, 546, 551 and 556 of the numerical registers to battery and ground. The numerical registers are thereby restored to their normal position at which time a series circuit is completed from ground through the brushes 558, 553, 548 and 543 in series, terminal 437, brush 415, contact and armature and winding of stepping magnet 416 to battery and ground. Magnet 416 restores the control switch to its normal position. When the control switch reaches its normal position a circuit is closed from battery through the winding of sequence switch magnet 440, left-hand contact 439 (10+18), terminal 479, brush 411, contact 438 to ground. Sequence switch 440 thereupon is restored to its normal position 1. 80

When the district sequence switch 210 leaves position 10½, the calling subscriber's line is disconnected at contacts 200 and 201 from the impulse circuit leading to the impulse relay at the register sender. Relay 400 thereupon becomes deenergized and after a sufficient interval of time the slow-to-release relay 404 retracts its armature, provided the sender sequence switch 440 is already restored to normal. As explained, a circuit is now completed from ground through the armature and back contact of relay 400, right-hand armature of relay 404, brush 411, terminal 479, contact 442 (1), upper right-hand contact 408 (4+18), winding of sequence switch magnet 410 to battery and ground. The class sequence switch 410 is thereby driven from position 10 into its normal position 1. 100

With the district sequence switch 210 in position 15 and the office sequence switch 310 in position 8 a conversational circuit is established through to the trunk 328, 329. When the calling subscriber later hangs up his receiver the circuit of relay 204 is 110 opened. Relay 204 in turn severs the holding circuit of relay 205 and this relay becomes deenergized. Relay 205, completes a circuit from ground through its right-hand normal contact, right-hand contact 219 (12+17), left-hand contact 219 (12+17), winding of sequence switch magnet 210 to battery and ground. Sequence switch 210 moves from position 15 into position 18. The district selector switch is restored to 120 125 130

normal in position 18 of sequence switch 210 by means of the down drive power magnet 226. A circuit for this magnet extends from battery through the winding thereof, 5 right-hand contacts 219 (18) to ground at the right-hand normal contact of relay 205. When the brush shaft 248 reaches its restored position a circuit is completed from battery through the winding of sequence 10 switch magnet 210, contact 217 (18), segment 229, brush 228 to ground at contact 223 (9+7). Sequence switch 210 thereupon moves into position 1. As sequence switch 210 leaves position 16 the upper right-hand 15 contact 222 is opened and the hereinbefore traced circuit of relay 300 is interrupted. Relay 300 releases its armatures and completes a circuit from battery through the winding of sequence switch magnet 310, 20 lower right-hand contact 303 (8+17), back contact and left-hand armature of relay 300 to ground. Sequence switch 310 leaves position 8 and moves into position 18. In this position the office selector switch is restored 25 to its normal position by the down drive power magnet 319. The circuit for magnet 319 may be traced from battery through the winding thereof, lower left-hand and upper right-hand contacts 301 (18) to ground. 30 When the switch shaft 326 is in its normal position sequence switch 310 is driven out of position 18 and into position 1 by means of a circuit from battery through the winding of the power magnet of said sequence 35 switch, upper right-hand contact 303 (3+18), segment 313, brush 312 to ground.

At the time relay 205 becomes deenergized it opens at its left-hand armature and contact the circuit which up to this time has 40 been holding the relays 206 and 104 actuated. Relay 104, on deenergizing, completes a circuit as follows for restoring the individual line switch to its normal position: battery, through the winding and armature and contact of stepping magnet 105, lowermost armature and contact of relay 104, right-hand armature and back contact of relay 103, brush 107, segment 112 to ground. The stepping magnet 105 interrupts its own circuit 45 and restores the brushes 106, 107, 108, etc. to their normal position where the brush 107 disengages segment 112 and severs the operating circuit of said stepping magnet.

The circuits of the system disclosed herein 50 are arranged to cause the registration of a certain code in response to the transmission of a single series of impulses from the subscriber's station. For example, if a called subscriber wishes to converse with an operator it is desirable that only one 55 digit be dialled, such as the digit 0. As will presently be explained, when the subscriber dials the digit 0 to permit a series of ten impulses, the translator switch is caused to step its brushes to the tenth

level and then to automatically rotate said brushes to the first set of terminals in this level. Referring particularly to Fig. 5, assume that the brushes 511, 512, 513, 514, etc., have been advanced opposite the tenth level of 70 terminals in their respective sections responsive to the transmission of a series of ten impulses. At this time the auxiliary brush 518 is engaging the tenth terminal 519 in the row 517. As soon as relay 500 releases its armatures following the deenergization of the slow to release relay 405, a circuit is closed from ground through the outer right-hand armature and contact of relay 500, brush 518, terminal 519, left-hand armature 80 and contact of relay 501, conductor 426, winding of relay 405, brush 412, terminal 417, conductor 424, inner right-hand armature and back contact of relay 500, conductor 561, winding of rotary magnet 503 to battery and ground. Magnet 503 rotates the brushes 511, 512, 513, etc. into engagement with the first terminal of the tenth level of the respective sections. At the same time the first step of the rotary magnet 502 rotates 90 the brush 518 out of engagement with terminal 519. The disengagement of brush 518 with terminal 519 opens the circuit of magnet 503 and the switch comes to rest. As above explained, the class sequence switch 95 410 leaves position 3 and commences to rotate following the setting of the translator switch. Relay 471 in this case becomes energized when sequence switch 410 reaches position 14. The circuit for relay 471 may be 100 traced from the winding of said relay, upper left-hand contact 472 (14), contact and outer right-hand armature of relay 501, terminal 521, brush 511 to ground. Since the translator switch is standing on the 105 first terminals in the tenth level, it will determine, according to the manner in which these terminals are wired to the counting relays, the operation of the district and office switches in such a manner as to select 110 a trunk line leading to the operator's position (not shown). The release of the apparatus takes place in exactly the same manner as hereinbefore described.

What is claimed is:

1. In a telephone system, a telephone line, an automatic switch having a plurality of line extending positions for extending said line, a selective switch having a plurality of differing directed movements, means for transmitting successive series of impulses over said line to said selective switch, means responsive to said impulses for operating said selective switch, and means operated in accordance with the position taken by 120 the selective switch for directly controlling the positioning of said automatic switch.

2. In a telephone system, a telephone line, a plurality of selectively operable automatic switches having a plurality of line extend- 130

- ing positions for extending said line, a selective switch having a plurality of differing directed movements, means for transmitting successive series of impulses over said line to said selective switch, means responsive to said impulses for variably positioning said selective switch, and means operated in accordance with the position taken by the selective switch for directly controlling the positioning of said automatic switches. 5
3. In a telephone system, a subscriber's line, automatic switches having a plurality of line extending positions for extending said line, a selective switch having a plurality of differing directed movements, means at the subscriber's substation for transmitting successive series of impulses over said line to said selective switch, means responsive to said impulses for operating said selective switch, and means operated in accordance with the position taken by the selective switch for directly controlling the positioning of said automatic switches. 10
4. In a telephone system, a subscriber's line, automatic switches having a plurality of line extending positions for extending said line, a selective switch having a plurality of differing directed movements, means for transmitting series of impulses over said line to said selective switch, means responsive to each of said series of impulses for operating said selective switch in one of its movements, and means operated in accordance with the position taken by the selective switch for directly controlling the positioning of said automatic switches. 15
5. In a telephone system, a subscriber's line, automatic switches having a plurality of line extending positions for extending said line, a selective switch having a plurality of differing directed movements, a sender at the subscriber's substation for transmitting series of impulses over said line to said selective switch, means responsive to each of said series of impulses for variably operating said selective switch in its different movements, and means operated in accordance with the position taken by the selective switch for directly controlling the positioning of said automatic switch. 20
6. In a telephone system, a telephone line, automatic switches for extending said line, a unitary selective switch having a plurality of separate directed movements, means for transmitting impulses over said line to said selective switch, means responsive to said impulses for variably positioning said selective switch, and a variably operable sending mechanism operated in accordance with the position taken by said selective switch for controlling the operation of said automatic switches. 25
7. In a telephone system, a telephone line, an automatic switch for extending said line, a unitary selective switch having a plurality of separate directed movements, means for transmitting impulses over said line to said selective switch, means responsive to said impulses for variably positioning said selective switch, a sending mechanism including a series of counting relays, means for operating a variable number of said counting relays depending upon the position taken by said selective switch, and means controlled by said counting relays for operating said automatic switches. 30
8. In a telephone system, a telephone line, automatic switches having a plurality of line extending positions for extending said line, a selective switch having a plurality of differing directed movements, an impulse circuit including said telephone line, means for extending said impulse circuit to said selective switch, means for transmitting successive series of impulses over said circuit, means responsive to said impulses for operating said selective switch, and means dependent upon the position taken by said selective switch for directly controlling the positioning of said automatic switches. 35
9. In a telephone system, a telephone line, automatic switches having a plurality of line extending positions for extending said line, a selective switch having a plurality of differing directed movements, an impulse circuit including said telephone line, a switch for extending said impulse circuit to said selective switch, means for transmitting series of impulses over said circuit, means responsive to such impulses for variably operating said selective switch, and means dependent upon the position taken by said selective switch for directly controlling the positioning of said automatic switches. 40
10. In a telephone system, a telephone line, automatic switches having a plurality of line extending positions for extending said line, a selective switch having two differing directed movements, means for transmitting successive series of impulses over said line to said selective switch, means responsive to said impulses for operating said selective switch, and means operated in accordance with the position taken by the selective switch for directly controlling the positioning of said automatic switches. 45
11. In a telephone system, a telephone line, automatic switches having a plurality of line extending positions for extending said line, a selective switch having a plurality of step-by-step movements, means for transmitting impulses over said line to said selective switch, means responsive to said impulses for variably operating said selective switch, and means operated in accordance with the position taken by the selective switch for directly controlling the positioning of said automatic switches. 50

12. In a telephone system, a telephone line, automatic switches having a plurality of line extending positions for extending said line, a selective switch having a vertical 5 and a rotary movement, means for transmitting impulses over said line to said selective switch, means responsive to said impulses for variably operating said selective switch, and means operated in accordance with the 10 position taken by the selective switch for determining through the directive control of said means the positioning of said automatic switches.
13. In a telephone system, a telephone line, automatic switches having a plurality 15 of line extending positions for extending said line, a selective switch having a plurality of step-by-step movements, means for transmitting series of impulses over said 20 line to said selective switch, means responsive to one of such series of impulses for stepping said switch vertically, means responsive to another of said series of impulses for stepping said switch horizontally 25 to its set position, and means operated in accordance with the position taken by the selective switch for determining through the directive control of said means the positioning of said automatic switches.
14. In a telephone system, a telephone line, automatic switches for extending said line, a unitary selective switch having a plurality of separate directed movements, a bank of terminals for said switch, means for transmitting impulses over said line to said 30 selective switch, means responsive to said impulses for variably operating said selective switch to select a set of said terminals, a sender comprising a series of relays, said 35 relays being variably connected to said terminals, means dependent upon the set of terminals selected by said selective switch for variably operating said relays, and means controlled by said relays for determining the 40 operation of said automatic switches.
- 45

In witness whereof, I hereunto subscribe my name this 26th day of October, A. D. 1920.

WALTER P. ALBERT.
